Attorney

UNITED STATES PATENT OFFICE

ROLLAND G. WILLIAMS, OF BRANFORD, CONNECTICUT, ASSIGNOR TO MALLEABLE IRON FITTINGS COMPANY, OF BRANFORD, CONNECTICUT, A CORPORATION OF CONNECTICUT

GUY FIXTURE FOR POLES

Application filed August 12, 1931. Serial No. 556,703.

REISSUED

My invention relates to guy attachments for poles, but more particularly aims to contrive a construction, similar to that shown and described in my Letters Patent No. 5 1,742,839, issued January 7, 1930, in which the guy cable may be disposed so that it will more nearly approach parallelism to the pole than the cable illustrated in the patent aforesaid.

10 In said patent the guy cable diverges at a wide angle from the pole and any anchorage of such cable which would tend to draw the latter toward the body of the fixture would loosen the spike or lag screw at the top of 15 the fixture, and the main object of the present improvement is to obviate this disadvantage.

Referring to the accompanying drawings, Figures 1 and 2 are elevation views at 20 right angles to each other, showing the fixture secured to the pole with the guy in position, both the pole and the guy being broken away, and

Figure 3 is a section at the line 3—3 of 25 Figure 1.

Similar numerals of reference denote like parts in the several figures of the drawings.

1 is the pole and 2 generally denotes the fixture which consists of a comparatively 30 broad base portion 3 shaped to closely conform to the pole, and from this portion a hub 4 extends outwardly and is pierced as shown at 5.

6 is a downward extension from this base, 35 and near its end this extension is also pierced and a spike 8 is driven through this extension into the pole.

A bolt 9 is passed through the piercing 5 and through the pole and the end of this bolt 40 is extended beyond the pole and is threaded and a washer 10 and nut 11 applied, as usual, to secure this base firmly to the pole.

The hub 4 has a rib 12 around its upper and side portions which rib has a groove 13 45 to accommodate the cable, as will be presently explained, and extending from the sides of the base portion 3 where it merges into the extension 6 are lugs 14 which are in a plane lower than that of the ends of the 50 rib 12.

The guy cable is denoted by the numeral 15 and is passed around the base 3 and secured in the usual manner.

Any inward draft of the cable is resisted by the lugs 14 and will therefore tend to bind 55 the end of the extension 6 against the pole so that the spike 8 will not be loosened, and these lugs will also prevent the cable from contacting the pole.

The rib 12 holds the cable so that it cannot slip off the hub, but the lugs 14 not only prevent the cable from contacting the pole, but also prevent the loosening of the spike at the lower end of the extension 6 in the manner above described. 60 65

What is claimed is:—

1. The hereindescribed fixture for the attachment of a guy to a pole, comprising a base portion having an outwardly extending pierced hub and a pierced extension extending downwardly from said hub, said extension staked to the pole, and said hub having a grooved rib extending from its upper and side portions and said base having outwardly extending lugs between which and the ends of said rib a cable surrounding the hub is confined. 70 75

2. A guy fixture for a pole comprising a base portion having a pierced hub to accommodate a bolt for securement to the pole and a downwardly pierced extension for spiking the fixture to the pole, said hub having an interiorly grooved rib extending around its upper and side portions, and the fixture at the point where the said extension merges 80 85 into said hub having laterally extending lugs whereby when the cable is applied around the hub it will be confined between the ends of the rib and said lugs.

In testimony whereof I affix my signature 90 hereto.

ROLLAND G. WILLIAMS.
